CLAIM

The ornamental design for an ice cream package, as shown and described.

DESCRIPTION

FIG. 1 is a perspective view of an ice cream package showing my new design;

FIG. 2 is a top plan view thereof, the bottom plan view is similar to the top plan view thereof;

FIG. 3 is a front elevation thereof, the rear side elevation is similar to the front elevation shown; and

FIG. 4 is a right side elevation thereof, the left side elevation is similar to the right side elevation shown.
